UNITED STATES PATENT OFFICE.

CARL VOGELSANG, OF SOLINGEN, GERMANY.

SCREW-CUTTING MACHINE.

No. 852,641.

Specification of Letters Patent.

Patented May 7, 1907.

Application filed June 12, 1906. Serial No. 321,343.

To all whom it may concern:

Be it known that I, CARL VOGELSANG, a subject of the German Emperor, residing at Solingen, Germany, have invented new and 5 useful Improvements in Screw-Cutting Machines, of which the following is a specification.

This invention relates to a screw cutting machine which is so constructed that the 10 cutting tool travels along the rotating screw blank for a number of times, in order to gradually deepen the thread.

In the accompanying drawings Figure 1 is a side elevation, Fig. 2 a plan and Fig. 3 an 15 end view of the whole machine. Fig. 4, and especially Figs. 5, 6 & 7 are intended to illustrate the details of the invention in question.

The tappet or cam 1 serves to advance and retard the cutter and the tappet or cam 2 to 20 effect a radial drive of same against the bolt, while the tappet or cam 3 carries it along the bolt (axially) to be screwed. The tappets 1 & 2 are on the shaft 4, the tappet 1 being fixed, while the tappet 2 is loose and 25 is actuated by a special or separate gear in such a manner that it makes only one revolution while tappet 1 makes a number of turns. The tappet 3, which is on the shaft 5 has, on the other hand, the same number 30 of revolutions as the tappet 1. The drive of the tappets is effected by the pulley 20 on the shaft 21 on which is the device carrying the bolt to be screwed. The shaft 21 carries a spur wheel 22 which engages with a wheel 35 23 which, in turn, is connected with the wheel 24. This latter drives the wheel 25 on the driving shaft 4 which communicates its movement to the wheel 26 and its shaft 27. On this latter there is the spur wheel 28 40 which engages into the wheel 29 which is connected with the tappet 2. The tappet 3 is driven by the bevel gear 30, 31 which is actuated by the shaft 4.

Cam 1, which is substantially circular, with 45 the exception of a recess 33, is engaged by a roller 12 pivoted to one arm of a lever 6, the other arm of which engages a lever 13 secured to a rotatable and axially displaceable shaft 14. Lever 6 is pivoted at 34 to a vertically reciprocating slide 19 guided in suitable manner in the stationary frame of the machine. To shaft 14 is secured the tool-holder 8 carrying the cutting tool 7. One 50 end of shaft 14 is provided with a roller 9 that engages cam 3. A spring 16 surrounding shaft 14 and engaging lever 13 and bear-

ing 15, serves to rotate the shaft in the direction of the arrow, (Figs. 1, 2 and 3), so as to hold lever 13 in permanent engagement with lever 6. Besides this function, spring 16 60 has the tendency to push shaft 14 toward the left to hold roller 9 in engagement with cam 3. Slide 19 is provided with an upper roller 18 which is engaged by a wedge 10 carrying a roller 11 that engages cam 2. Roller 11 is 65 held against cam 2 by a lever 17 engaging wedge 10 and influenced by a spring 36, while slide 19 is influenced by a spring 35.

As above stated, cams 1 and 3 make a series of rotations during the time cam 2 makes 70 a single rotation. Cam 1 serves to hold the cutter against the work-piece, while cam 3 advances the same along such work-piece. At the end of each forward movement of the tool, roller 12 will engage recess 33 of cam 1, 75 to allow spring 16 to withdraw the tool from the work-piece. Simultaneously, roller 9 will slide off the raised portion of cam 3 to permit spring 16 to return shaft 14 to its initial position. During the consecutive reciprocations and rotations of shaft 14, cam 2 will gradually advance wedge 10 to raise slide 19 together with pivot 34 of lever 6. In this way the tool will gradually be brought 80 nearer to the axis of the work-piece, so as to 85 deepen the cuts. After the operation has been finished, slide 19 is again lowered, roller 11 of wedge 10 engaging the reduced section of cam 2.

If it is required to cut longer or shorter 90 screws the tappet 3 is interchanged for a larger or smaller one and, in order that the bolt or work in hand perform the correct number of revolutions, the wheels 22 and 23 are changed. In the same manner, when it 95 is required to cut a deeper thread, the tappet 2 can readily be changed, or the position of the cutter or the driving mechanism can be altered.

Having now fully described my invention, 100 what I claim as new and desire to secure by Letters Patent is:

1. In a screw cutting machine, a cutting tool, a first cam, means controlled by the first cam for bringing the tool into or out of 105 engagement with the work-piece, a second cam, means controlled by the second cam for gradually advancing the tool toward the axis of the work-piece, and a third cam for advancing the cutting tool along the work-piece, substantially as specified.

2. In a screw cutting machine, a cutter-

shaft, a first cam and a slide, combined with a lever fulcrumed to the slide and engaging said first cam, a second cam, means controlled by the second cam for raising and lowering the slide, and means for operatively connecting the cutter-shaft with the lever, substantially as specified.

3. In a screw cutting machine, a cutter-shaft, a first cam and a slide, combined with a lever fulcrumed to the slide and engaging said first cam, a second cam, means con-

trolled by the second cam for raising and lowering the slide, a third cam adapted to reciprocate the cutter-shaft, and means for operatively connecting the lever with the cutter-shaft, substantially as specified. 15

Signed by me at Düsseldorf, Germany, this twenty-ninth day of May 1906.

CARL VOGELSANG.
